[57] **CLAIM**

The ornamental design for an element for ski pole handle or similar article, as shown and described.

DESCRIPTION

FIG. 1 is a side elevational view of an element for ski pole handle or similar article showing my new design; FIG. 2 is a side elevational view of the side opposite that shown in FIG. 1;

FIG. 3 is a top plan view thereof;

FIG. 4 is a bottom plan view thereof;

FIG. 5 is an end elevational view thereof; and,

FIG. 6 is an end elevational view opposite that shown in FIG. 5.

FIG. 1

FIG. 2

FIG. 3

FIG. 4

FIG. 5

FIG. 6
